Primary Examiner — Kevin K Rudzinski*Assistant Examiner* — Kathleen L Jones(74) *Attorney, Agent, or Firm* — Perkins Coie LLP(57) **CLAIM**

The ornamental design for a center link assembly, as shown and described.

DESCRIPTION

FIG. 1 is a perspective view of a center link assembly.

FIG. 2 is a front plan view thereof.

FIG. 3 is a back plan view thereof.

FIG. 4 is a right view thereof.

FIG. 5 is a left view thereof.

FIG. 6 is a top view thereof; and,

FIG. 7 is a bottom view thereof.

The broken lines in FIGS. 1-7 showing portions of the center link assembly are included for the purpose of illustrating portions of the article and form no part of the claimed design.

Contrast in materials is shown herein by using line shading in one area and stippling in another in accordance with MPEP § 1503.02(II).
